UNITED STATES PATENT OFFICE.

JESSE RABB, JR., OF YOUNGSTOWN, OHIO.

SAFETY DEVICE FOR PLATFORMS.

Application filed March 1, 1923. Serial No. 622,110.

To all whom it may concern:

Be it known that I, JESSE RABB, Jr., a citizen of the United States, residing at Youngstown, in the county of Mahoning and State of Ohio, have invented certain new and useful Improvements in Safety Devices for Platforms, of which the following is a specification.

This invention relates to safety devices for use in connection with railroads and has for its object to provide station platforms with an automatically actuated guard to prevent passengers from accidentally falling from the platform on the railroad track.

15 A further object of the invention is to provide means whereby the vertically movable guard may be so connected with the conventional air brake system that the guard may or may not be lowered by the train, according to whether the same is a local or an express. A still further object of the invention is to provide means releasable by instrumentalities connected with the train whereby the guard will be positively maintained in its operative upright position until released by the said instrumentalities, thereby preventing accidental or surreptitious lowering of the guard when the train is absent. Other objects will appear from a reading of the following detailed description in connection with the drawings appended hereto, and made a part hereof.

In the drawings,

Figure 1 is a top view partly in section of the apparatus. Figure 2 is a cross-sectional view of the platform and the railway car disclosing the operating mechanism. Figure 3 is a detail view of the pawl and ratchet mechanism for maintaining the guard in a definite position, and Figure 4 is a sectional view of the railway car disclosing the tripping mechanism and the operating connections therefor.

Referring now more particularly to the drawings wherein like reference characters indicate corresponding parts, A designates the conventional passenger platform, B a well or pit formed therein, providing means for receiving the reciprocating weight C, which has attached thereto the cable D connected at its outer end to the reciprocating guard E. It will, therefore, be seen that the weight normally tends to maintain the guard in its upright operative position. The guard E has attached thereto a cable F, which cable is maintained in position at its lower end

by means of a pivotal roller G. The cable passes around this roller and is connected at its outer end with a slidabale abutment H. The train is provided with a trip mechanism I which is adapted to engage the said abutment and slide the same longitudinally with respect to the track, which movement results in the lowering of the guard by means of the cable F. In order to positively maintain the guard in its upright position when the train is not adjacent the passenger platform, the wall is provided with a member having teeth K which are engaged by a spring pawl L, which pawl is connected with a further cable M. The said cable M is also maintained in a vertical position with respect to the platform by means of a second pivotally mounted roller N, and is likewise connected at its other end with the said sliding abutment H. It will, therefore, be seen that upon actuation of the sliding abutment H by the trip member I that both cables will be operated, one to release the pawl and ratchet mechanism, and the other to lower the guard in opposition to the weight C. It will be seen that after the train passes the passenger platform the weight will automatically raise the guard, which guard will be again secured in its upright position by the spring pawl L. The vertical movement of the weight will likewise pull back the abutment H to its normal position by means of the cable F attached to the lower end of the guard. O represents a connection with the conventional air line for the braking system of a railroad by means of which the operator of an express car may cause a depression of the plunger P by the actuation of a suitable valve Q. When the piston is depressed it will move the member U transversely with respect to the train, which movement of said member will rock the trip I to an offset position, in which position the said trip will be out of line with the plunger H, and thereby be inoperative so that the position of the guard will not, when the plunger is caused to assume this position be disturbed. It will be noted that the plunger is pivoted to the car at S to permit such rocking motion. However, the normal position of the plunger will be vertical so that the device, unless operated as aforesaid will be operative.

It will be understood by those skilled in the art that many changes in the construction, arrangement and operation of the parts

may be used without departing from the spirit of the invention, as expressed in the appended claims.

Having thus described my invention, what I claim is:

5. 1. A safety apparatus for passenger platforms, comprising a vertically movable safety guard, a weight connected with said guard for automatically maintaining the same in its operative upright position, means for pulling down said guard to its inoperative position by instrumentalities connected with an approaching train.
10. 2. In a safety guard for railway platforms, means for automatically holding said guard in its upright position, of a railroad track, a slideable abutment associated with said track having connections with the movable guard, of a movable vehicle, and means associated with the movable vehicle for engaging the said slideable abutment to lower the railroad guard when the movable vehicle is adjacent the platform.
15. 3. A safety apparatus for railroad platforms comprising a vertically movable safety guard located in proximity to the platform, said platform having a well therein, a weight adapted to travel in said well, said weight being connected with said guard to normally maintain the same in its operative upright position, and instrumentalities connected with an approaching vehicle adapted to automatically lower the guard when the vehicle is adjacent the platform.
20. 4. A safety apparatus for railroad platforms, comprising a movable guard normally maintained in operative position controlling means for said guard located adjacent a railroad track, a trip mechanism associated with the train travelling on said track for engagement with the controlling means to automatically lower the same upon the approach of the train, said trip mechanism having connections with the air line of the train whereby the said trip mechanism may be moved to either operative or inoperative position.
25. 5. A safety apparatus for railway platforms comprising a movable guard normally maintained in an operative position, controlling means for said guard located ad-
55. jacent a railroad track, a trip mechanism associated with the train travelling on said track for engagement with the said controlling means to automatically lower the same upon the approach of the train, said trip mechanism being pivotally connected with the train and adapted to be laterally moved around its pivotal connection to render the same out of alignment with the controlling means on in operative relation therewith.
60. 6. In a safety apparatus for railway platforms comprising a movable guard located in proximity to the platform, said guard being maintained normally in an upright operative position, and a railway track adjacent said platform, controlling means located in close proximity to said track, connections between said controlling means and said guard for lowering the guard upon the approach of the train, a trip mechanism associated with said train and pivotally connected thereto and means for moving said trip mechanism around its pivotal connection to either an operative or inoperative position with respect to the said controlling means.
65. 7. The combination with the railroad platform of a movable guard disposed adjacent one edge thereof, a weight located in said platform, connections between said weight and said platform adapted to normally urge the platform in its operative upright position, said platform comprising a rack along the inner side thereof, a spring pawl associated with said guard, and adapted to engage said rack to positively maintain the guard in a definite position, and to prevent accidental lowering thereof of a railroad track, controlling means associated with said railroad track adapted to be actuated by an approaching train, connections between said controlling means and said guard and spring pawl adapted to be actuated by said controlling means to release said spring pawl from engagement with the rack and to lower the said guard against the force of said weight, upon the actuation of said controlling means by the approaching train.
70. 8. In testimony whereof I affix my signature.
75. 9. JESSE RABB, JR.
